SPOON WIPER

William Florio, 11 General McLean Drive,
Bellport, N.Y.

Filed Mar. 25, 1964, Ser. No. 79,193

Term of patent 14 years

(Cl. D44—29)

FIG. 1 is a front elevational view of a spoon wiper showing my new design;

FIG. 2 is a rear elevational view thereof;

FIG. 3 is a side elevational view thereof, the opposite side being the same;

FIG. 4 is a bottom end view thereof, looking in the direction of the arrows on line 4—4 of FIG. 1; and

FIG. 5 is a top end view thereof, looking in the direction of the arrows on line 5—5 of FIG. 3.

The dominant features of my design reside in the portion shown in full lines.

I claim:

The ornamental design for a spoon wiper, as shown and described.
